UNITED STATES PATENT OFFICE.

WILLIAM N. DICKINSON, JR., OF NEW YORK, N. Y., ASSIGNOR TO OTIS ELEVATOR COMPANY, OF JERSEY CITY, NEW JERSEY, A CORPORATION OF NEW JERSEY.

ANTIPHASE REVERSING DEVICE.

949,465.

Specification of Letters Patent. Patented Feb. 15, 1910.

Application filed July 3, 1906. Serial No. 324,541.

To all whom it may concern:

Be it known that I, WILLIAM N. DICKINSON, Jr., a citizen of the United States, residing in New York, borough of Brooklyn, 5 in the State of New York, have invented a new and useful Improvement in Antiphase Reversing Devices, of which the following is a specification.

My invention relates to a safety device for 10 interrupting electric circuits and although it is herein shown applied to motor-controlling circuits of an elevator system, it may have a general application.

The primary object of my invention is the 15 provision of automatic means for interrupting the connection between the source of power and a translating device when the latter does not operate as desired.

More particularly it is the object of the 20 present invention to provide means for automatically opening the main line switch connected to an electric motor if the latter does not operate in the desired direction by reason of reversal of current relations on the 25 main line.

Another object of my invention is the provision, in an elevator system, of means for controlling the opening of the main lineswitch for the motor, from a predetermined point.

30 Other objects of the present invention will appear hereinafter, the novel combinations of elements being pointed out in the claims.

The accompanying drawing illustrates the 35 principles of my invention and shows the application thereof to an electric elevator system.

The invention is particularly adapted to 40 be used in connection with a torque-release brake such as described in my co-pending application, Serial No. 320,957, filed June 9, 1906, for an improvement in protective apparatus for alternating current elevators.

The present invention is embodied in an 45 elevator system and assumes the nature of a protective device therefor in that it automatically opens the main line switch and thus interrupts the current to the motor to effect the stopping thereof. Furthermore such protective device may be operated by 50 means of a slack cable switch, hatchway limit switches, or by means of a safety switch in the car.

Accidents and the derangement of control in connection with alternating current mo-

tors of the multiphase type, have from time 55 to time occurred when used in elevator systems owing to unexpected change in phase relation of the current either on the lines exterior to the building or to changes in connections in the building. One of the means 60 employed as a protection against such accidents or derangement of control has involved the principles of the revolving field as made use of in the multiphase induction motor. Windings necessary to produce a 65 revolving magnetic field in a stationary frame when energized with multiphase current, are placed in such relation to a secondary member that a torque is generated between the two members; its direction 70 depending upon the relation between the phases. A main circuit switch is held in closed position against the action of gravity or a spring by the above-mentioned device when the relation between the phases is 75 that for which the elevator controlling devices have been adjusted. Should the phase relation be reversed, however, the direction of torque in the protecting device would be 80 reversed and the main line switch would be opened. The parts of the device are so proportioned that they might remain in stationary condition indefinitely without damage from overheating. In the present invention provision is made to open the main line circuit 85 in the event of phase reversal, with the addition of but small cost to a specific power motor arrangement, and without the consumption of other than a momentary current.

On the bed plate B is mounted the motor M having a movable stator frame 1. This stator frame is provided with journals 4 mounted in the bearings 2 at the upper ends of the standards 3. The journals 4 act as 95 bearings for the rotor shaft 5, rigidly connected in this instance is a downwardly projecting arm 6 which carries the armatures 18, 18' of the holding magnets 17, 17'. The latter act as stops for limiting the rotative 100 movement of the stator frame 1.

As explained in my co-pending application hereinbefore referred to, the armature 18 or 18' engages with the poles of the magnet 17 or 17' to close the magnetic circuit thereof before or substantially at the same time that the contacts 21 supported by the insulating extension 19 engage the

fixed contacts 20 or 20'. It will be seen that the movable contacts 21 are connected by means of the leads 36 to the motor terminals 35, so that when the contacts 21 engage the fixed contacts 20 or 20' the solenoids of the magnet 17 or 17' will become excited with current and the stator frame held firmly in its limiting position after being moved to either limit of rotative movement by the torque of the motor when starting. Also carried by the insulating extension 19 of the arm 6 is a contact 22 adapted to engage and electrically connect the contacts 44 or 44'. The latter contacts are connected to auxiliary switches co-acting with the reversing switches, said auxiliary switches being connected to one of the tripping coils for operating the releasing device of the main line switch L.

20 For the purpose of illustration I have shown a simple main line switch and releasing mechanism therefor, but it should be understood that the details thereof may be varied by those skilled in the art without departing from the principles of my invention.

a, b, c designate the main lines connecting the source of supply to the switch contacts 23, 24, 25.

30 *a', b', c'* indicate continuations of the main line to the reversing switches R, R'. The insulating lever 22 which carries the movable contacts of the main line switch, is shown pivoted at 27 and provided with a handle 26. Normally the main line switch L is held in closed position by means of the latch 28 which is pivoted at 29. Rigidly connected with the latch 28 is an arm 30 extending over the tripping electro-magnets 31, 32 and 33 so as to lie in the path of travel of the cores of said electro-magnets. The electro-magnets 31 and 33 are connected in the circuits *a', c'* respectively, whereas the electro-magnet 32 is connected between 35 the circuit *b'* and the auxiliary switches comprising the contacts 39, 42, and 39', 42'. Should the main line current increase to a predetermined unsafe value while the motor is in operation, or when one of the reversing 40 switches is closed, either the electro-magnet 31 or 33 or both would be operated to effect the actuation of the latch 28 and the consequent release of the arm 22' and the opening of the main line switch L. The current being thus cut off from the motor, any suitable 45 brake provided therefor will be automatically applied and a centering device would bring the arm 6 back to central position as shown in the drawing.

60 If desired, the motor M may be connected to operate hoisting apparatus E which comprises a hoisting drum connected by means of the cable 78 over the sheaves 79 and 80 to the car C. If the car switch S is actuated 65 so as to cause the car to be moved upwardly,

one of the reversing switches R or R' will be closed and also one of the auxiliary switches connected to the electro-magnet 32. For instance, if the lever 90 is moved onto the contact 89, a circuit will be closed from the lead *c'* through wire 91, magnet 85', wire 92, contacts of the automatic machine limit switch 83, wire 96, contact 89, lever 90, wire 97, slack cable switch 88, wire 100, to one of the other leads *a', b'*; in this case that 70 designated *b'*. The reversing switch R' will thereupon be closed and the stator of the motor M will receive current to rotate the stator frame in one direction or the other, say in a clock-wise direction, to effect the release of the brake and the energization of the holding magnet 17. The rotor will then be free to rotate to operate the hoisting apparatus to move the car upwardly. Now if the motor has operated in 85 the proper direction, no circuit will be closed through the electro-magnet 32 by the engagement of the contact 22 with the fixed contacts 44. If it is attempted to trace a circuit through the electro-magnet 32 it will 90 be found that the closed auxiliary switch is connected to one of the contacts 44', whereas the contacts 44 engaged by the contact 22 are connected by means of the wire 41 to the open contact 42. It will therefore 95 be seen that the contacts 44, 44', and the auxiliary switches are so arranged and connected that the circuit to the central tripper coil 32 of the three-pole main line switch is not completed when the stator is rotated in 100 the direction in which it would be normally rotated by the initial torque when the relation between the phases of the line current is that for which the automatic stops have been adjusted, and the car switch connected. 105 If, however, the phase relation of the main line has been reversed, the stator will be thrown by the initial torque in the opposite direction to that in which it would be normally rotated for the predetermined movement of the car switch, and the circuit to the middle tripping coil will be immediately completed, and the three-pole switch at once opened and the elevator motor, hoisting apparatus and car brought to rest. For 110 instance, if the phase relation of the main line current has been reversed and the car switch is moved onto contact 89 as before, the reversing switch R' will be closed and the stator frame 1 moved in an anti-clock-wise direction. The contacts 44' will then be connected by the movable contact 22 and a circuit will be closed from the lead *c'* through the wires 40, 46, and 45', contacts 44' and 22, wire 41', contact 42', bridge 115 piece 43', contact 39', wire 87, coil 32, to the lead *b'*. It will therefore be seen that the tripper coil 32 will receive current and consequently the arm 30 will be struck by the core movable within the coil 32, and the 120 125 130

latch 28 will therefore release the arm 22 to permit the main line switch L to automatically open.

As before stated, when the main line switch 5 is thus opened, the stator frame will return to its normal position and the brake applied to stop the motor and hold the car in stationary position. For the sake of clearness and to prevent confusion, I have not herein 10 shown the centering device or brake apparatus as it is no part of the present invention, such device and apparatus being described and claimed in combination with my co-pending application hereinbefore referred 15 to. It should also be observed that should the car pass beyond the limits of its travel for which the hoisting machine automatics are adjusted, either one or the other of the hoistway limit switches 81 or 82 will be 20 closed by the cam 103 on the car. In such event a circuit through the middle tripping coil 32 will be closed, and consequently the main line switch L opened and the car brought to rest. If the limit switch 81 is 25 closed, a circuit is established from the lead c' through the wires 40 and 47, wire 98, switch 81, wire 99, coil 32 to lead b'. It will also be noted that the same object 30 may be accomplished by closing the safety switch 48 in the elevator car itself, and that on the opening of the main line switch L from any cause, it will be impossible to again start the car except by first manually closing said switch L. The circuit closed 35 by the safety switch 48 in the car may be traced from the lead c' through wires 40 and 50, switch 48, wire 49, wire 99, coil 32 to lead b'.

The safety apparatus is purposely so 40 designed that it will be necessary to manually close the main line switch L which is usually placed on a controller board adjacent the hoisting apparatus. This is for the reason that none of the three above-mentioned 45 circuit closing conditions would obtain under circumstances other than those making an inspection of the elevator machine by the attendant, desirable. The series coils 31 and 33 are placed on the two outside circuits of 50 the three-pole switch to open the main line circuit when excessive current flows therethrough, due either to excessive potential or load, defective motor windings, low periodicity, or the blowing of a fuse on any 55 one of the three legs of the circuit thus turning the current supply to the motor from multiphase to single-phase.

I have shown my invention in connection 60 with an ordinary multiphase induction motor of the squirrel cage type, but it is also applicable to direct current motors or to any form of alternating current or direct current apparatus in which the action of the brake simultaneously with, or approximately 65 simultaneously with, the application or in-

terruption of power, or current to the motor, is desired. It is obvious that those skilled in the art may make various changes in the details and arrangement of parts of my invention without departing from the 70 principles thereof, and I desire therefore not to be limited to the precise construction herein disclosed.

Having thus fully described my invention, what I claim and desire to have protected 75 by Letters Patent of the United States is:—

1. The combination with a motor comprising a frame having a limited revoluble movement, of a main line switch, tripping apparatus therefor, reversing switches, auxiliary switches coöperating with said reversing switches, and safety switches operated by the revoluble frame of the motor and co-acting with said auxiliary switches to effect the operation of the tripping apparatus 85 when the motor turns in a wrong direction.

2. In an elevator system, the combination with a car, hoisting apparatus and motor, of motor-controlling apparatus, a normally open safety switch in the car, and means 90 operated by the closing of said safety switch for cutting of the main line current to the system.

3. The combination with a motor having one part arranged for continuous movement 95 and the other for limited movement, of controlling apparatus therefor, and means dependent upon said other part for effecting a stopping of the motor when the latter starts in the wrong direction.

4. The combination with an electric motor having one member arranged to rotate continuously and the other member to have a limited rotative movement, of an electric switch operated by said other member, and means 105 controlled by said switch to effect the cutting off of current from the motor when the latter starts in a direction contrary to that selected.

5. The combination with a motor having 110 an inner rotative member and an outer member mounted to have a limited degree of rotation, of controlling apparatus for said motor, a switch arranged to be closed upon movement of said outer member, and means 115 controlled by said switch for effecting a stopping of the motor upon the latter starting to rotate in a direction contrary to that selected.

6. The combination with an induction 120 motor having a stator frame mounted for a limited rotative movement, of an arm connected to said frame to move therewith, a circuit-closing member carried by said arm, a plurality of contacts in the path of movement of said circuit-closing member and engaged thereby when said frame rotates, and means controlled by said circuit-closing member and contacts for cutting off current to the motor to stop the same upon the latter 125 130

starting in a direction contrary to that selected.

7. The combination with an electric motor having a frame mounted for a limited degree of rotative movement, of an electro-magnet for holding said frame in its limited position, an armature carried by said frame and movable against said electro-magnet to close its magnetic circuit, a switch closing the electric circuit through said electro-magnet when its magnetic circuit is closed, additional switch mechanism operated by movement of said frame, and means controlled by said additional switch mechanism for cutting off current to the motor when the latter starts in a direction contrary to that selected.

8. The combination with an alternating current induction motor comprising a frame having a limited degree of rotative movement in either direction from its normal or central position, of two electro-magnets, one for holding the frame in one of its limiting positions and the other for holding said frame in the other of its limiting positions, an armature carried by said frame to close the magnetic circuit of either electro-magnet, switch mechanism operated upon movement of said frame to control the energization of said electro-magnets, direction switches for controlling the flow of current through said motor, a main line switch, electro-mechanical tripping appliances for opening said main line switch automatically, auxiliary switches connected to said direction switches, and additional switch mechanism operated by movement of said frame and co-acting with said auxiliary switches to effect the operation of said tripping appliances when the motor starts in a direction contrary to that selected.

9. In an elevator system, the combination with a car, hoisting apparatus and motor, of safety switches operated by a limited movement of the motor frame, a main line switch, electro-magnetic apparatus associated with said main line switch, motor-controlling means operable from the car, and auxiliary switches co-operating with said motor-controlling means and co-acting with said safety switches to effect the operation of said electro-magnetic apparatus to open the main line switch upon the motor starting or tending to start contrary to a predetermined direction.

55 10. In an elevator system, the combination with a car, hoisting apparatus and multi-

phase alternating current motor, of reversing switches controlled from the car, two safety switches associated with the motor, one or the other being operated upon a limited revoluble movement of the stator frame, a main line switch, means for holding the last-named switch closed, a tripping electro-magnet, and auxiliary switches associated with said reversing switches and co-acting with said safety switches to complete a circuit through said tripping electro-magnet to effect the opening of the main line switch when the relation of phases of the main line current is reversed and the stator frame moved in a direction opposite to that predetermined.

11. In an elevator system, the combination with a car, hoisting apparatus and multi-phase alternating current motor, of an arm carried by the revoluble stator frame, an armature carried by said arm, fixed electro-magnets in the path of movement of said armature and serving to limit the movement of the stator frame and hold the same in such limiting position in either direction, switch contacts adjacent the electro-magnets, a circuit-closer carried by said arm and engaging one set of such switch contacts when the stator frame is in limiting position, and means co-acting with said circuit-closer and contacts to open the main line upon reversal of phase relation of current and a rotation of the stator frame in a contrary direction.

12. In an elevator system, the combination with a car, hoisting apparatus and multi-phase induction motor, reversing switch apparatus comprising single-phase electro-magnets, a switch in the car for controlling said electro-magnets, means for holding said switch in closed position, a single-phase electro-magnet for tripping said holding means to permit the main line switch to open, auxiliary switches associated with said reversing switch apparatus, and safety switches operated by a limited movement of the stator frame and co-acting with said auxiliary switches to complete a circuit through said tripping electro-magnet upon a reversal of phase relation of main line current.

In testimony whereof, I have signed my name to this specification in the presence of two subscribing witnesses.
